CLAIM

The ornamental design for a dome theatre structure, substantially as shown and described.

DESCRIPTION

FIG. 1 is a front elevational view showing my new design for a dome theatre structure;

FIG. 2 is a rear elevational view thereof;

FIG. 3 is a side elevational view thereof;

FIG. 4 is a top plan view thereof; and

FIG. 5 is an enlarged fragmentary perspective view of a portion of the front entrance shown in FIG. 1.

FIG. 1

FIG. 2

FIG. 3

FIG. 4
